ADVERTISING DISPLAY

Ernst Borregard, Long Island City, N. Y., assignor to Fuller Displays, Inc., Long Island City, N. Y., a corporation of New York

Application February 12, 1942, Serial No. 430,565

4 Claims. (Cl. 46—119)

My present invention relates to display devices, and more particularly to an improved animated display device.

My improved invention is a display device of the animated type in which a plurality of figures, representing animals, persons or the like, have a simulated movement in order to attract the attention of the observer to the display and therefore to the goods it is desired to advertise thereby.

My device is designed to eliminate the main trouble of animated displays as are in use at the present time, namely, that such devices are too mechanical and the various movements of one object with respect to the other is predetermined and constant. My present invention affords the representation of a group of figures to each of which respectively is given individual movement which is independent of the movement of the combined figures but which individual movement viewed with the remaining figures simulates a combined action between the figures represented. However, the individual movement of the respective figures bears no relation whatever to the time of movement of any of the other figures, that is, the movement of any figure is not dependent on, or in time with, the movement of any other figure, nor is the degree or range of movement of any of the figures constant in any sense.

In carrying out my invention, I arrange a plurality of figures at spaced intervals along a pivotally mounted lever intermittently oscillated about its pivot point by electrical means. The figures are mounted on the lever preferably by spring means so that each figure will have a movement the extent of which is determined by the movement of the lever, and because of the spring mounting, each of such figures will have a movement independent of the movement of the spring and of greater or less amplitude, depending upon the stiffness or flexibility, as well as the length of its mounting spring.

The object of my invention, therefore, is an improved animated display device.

In the accompanying drawing:

Fig. 1 is a front elevation of a display device and made according to my present invention;

Fig. 2 is a rear elevation of the structure shown in Fig. 1, part of the structure being shown in section and having associated therewith the electric control means for imparting oscillatory movement to the figure-holding lever;

Fig. 3 is a plan view of the structure shown in Figs. 1 and 2;

Fig. 4 is a sectional end elevation taken on the line 4—4 of Fig. 2; and

Fig. 5 is a sectional end elevation taken on the line 5—5 of Fig. 2.

Referring to the drawing, 10 designates a base of any desired dimensions suitable for the display to be made or mounted thereon. Pivottally

mounted on the base 10 by hinge 11 is a lever 12, as shown in Fig. 2. The hinge 11 may be screwed to the under face of the lever 12 and the same may be attached to the base 10 by the pronged staple 13, which also acts as the pivot for the hinge 11, see Fig. 5. At one end of the base 10 is a notch or groove 10a, in which is housed a solenoid 14. Preferably, I fasten to the bottom surface of the end of the base 10 a plate 15 which may be of cardboard or any other suitable material, to provide a bottom for the notch or groove 10a, and thus prevent the solenoid 14 from falling out of position should such solenoid 14 not be a sufficiently snug fit in the groove 10a. The solenoid 14 is energized from any suitable source of power through the conductors 16 and 17, and in one of the conductors, as the conductor 16, is a heating coil 18 for controlling the operation of a bi-metallic thermostat 19, such bi-metallic thermostat being shown connected in the conductor 17 and controlling the circuit through such conductor at the contact points 20.

One end of the lever 12 is provided with a notch or groove 21, slightly larger in width than the diameter of the solenoid 14, so that upon oscillation of the lever 12, the upper end of the solenoid 14 will be received within the groove 21. Secured to the grooved end of the lever 12 is a plate 22 of non-metallic material and provided with a perforation in alignment with the interior of the solenoid 14. Resting on top of the plate 22 is a disc or washer 23 of non-metallic material, as rubber, and through such washer extends a bolt 24 which acts as an armature for the solenoid 14.

When the bi-metallic thermostat 19 is in a cool condition, the contacts 20 are closed, thereby completing the circuit through the conductors 16 and 17 and the solenoid 14, and thereby energizing the solenoid 14 so as to attract the armature 24 and rotate or oscillate the lever 12 about the hinge 11 in clockwise direction as viewed in Fig. 2. The completion of the circuit also completes the circuit through the heating element 18. As the mechanically biased end of the lever 12 moves downward, it will remain down until the heating element 18 has heated the bi-metallic thermostat sufficiently to break the circuit through conductor 17 at the contacts 20, whereupon the distribution of the weights on the lever 12 will cause the lever to move back into the position shown in Fig. 2.

There may be mounted on the lever 12 at various points along its length a number of figures or symbols or any advertising matter as may be desired. I have shown adjacent the pivot hinge 11 a standard 25, to the upper end of which is secured one end of a spring 26, and on the other end of such spring through the intermediary of a member 27 is secured the figure of an animal

28, such as the figure of a cat. The movement of the figure 28 is thus of limited amplitude, although given considerable scope. As the lever 12 rotates or oscillates about the hinge 11, the member 25 will move in synchronism therewith, and the spring 26 to which is attached the figure 28 will impart to the figure 28 not only the movement of the member 25 but also an additional and independent movement, depending on the length and resiliency of the spring 26.

At the end of the lever 12 adjacent the notch or groove 21 is secured a block 29, and to this block is secured the lower end of a spring 30. At the upper end of the spring 30 is secured, through the intermediary of block 31, the figure of an animal 32, as a dog. By comparison with the figure of the cat 28, it is obvious that the figure of the dog 32 will have a much more animated movement than such cat, due primarily to not only the employment of the relatively long spring 30, but also to the absence of the relatively stiff mounting 25, as in the case of the cat 28. As the lever 12, therefore, oscillates, the cat 28 will be given a certain degree of movement, as will also the figure of the dog 32, but the amplitude of movement of the dog 32 will be so much greater than that of the cat 28 that it will appear to the observer that the dog is making energetic effort in chasing the cat.

In the present instance, the mounting for the cat 28 is on one side of the pivot hinge 11, while the mounting for the dog 32 is on the other side, and it has been found that this gives the best range of movement for the purpose desired. On the same side of the pivot hinge 11 as the cat 28 and more nearly adjacent the end of the lever 12 is a member 33, to which is secured a rather long and relatively more flexible spring 34, and to the upper end of the spring 34 is secured the figure of an animal 35, such as a mouse or rat. It is clear that because of the character of the mounting of the animal 35 as compared with either the mounting 25 for the cat 28 or the mounting for the dog 32 that the mouse 35 will have a greater range of movement than either of such animals, and because of such relation to the cat 28 will have the appearance of being chased by the cat.

It will be seen that there is no constant relationship between the movement of the cat 28, dog 32 or mouse 35 other than there will be a mutual association of all of these figures with respect to each other. The movement of the cat 28 is short but continuous, and of a relatively fixed amplitude. The movement of the dog 32 is constant, but its range or amplitude of movement is undeterminable, as is also the range or amplitude of movement of the mouse 35. Not only is this so, but because of the amplitude and range of the dog 32, the action of the lever 12 is undeterminable, regardless of the fact that the strength of current through the heating coil 18 may be constant. If the figure of the mouse, for example, and referring to Fig. 2, is close to the cat 28 when the bi-metallic element of the thermostat 19 has come into engagement with the contacts 20 to close the circuit through the heating coil 18, the energy imparted to the solenoid 14 will be sufficient to quickly energize the solenoid 14 and cause a quick or rapid oscillation of the lever 12. On the contrary, if the figure of the mouse 35 is distant from the cat 28 or considerably to the left, as shown in Fig. 2, then under like circumstances the energy imparted to the

solenoid 14 will be insufficient for a measurable length of time to impart an oscillatory movement to the lever 12. Further, all of the above factors are further modified by the use of a block 36 of any suitable material which may be arranged at any point along the top of the lever 12.

As a setting or background for the figures illustrated in this embodiment of my invention, I may utilize a sheet 37 of cardboard, ornamented as shown in Fig. 1, and at one end thereof fixed so as to simulate a box or fence 38 behind which the mouse 35 periodically disappears in its attempt to escape from the cat 28.

Whereas I have described my invention by reference to specific forms thereof, it will be understood that many changes and modifications may be made without departing from the spirit of the invention.

I claim:

1. An animated display device comprising in combination a base, a lever pivotally mounted on the base, means for oscillating the lever, a plurality of display figures, and differentially resilient means for mounting the display figures individually on the lever, whereby upon oscillatory motion imparted to the lever differential movement is imparted to the respective display figures.

2. An animated display device comprising in combination a base, a lever pivotally mounted on the base, means for oscillating the lever, a plurality of display figures, and differentially and serially arranged means for mounting the display figures individually on the lever, whereby upon oscillatory motion imparted to the lever differential movement is imparted to the respective display figures.

3. An improved animated display device comprising in combination a base, a lever pivotally mounted on the base, means mounted on the base and on the lever for imparting oscillatory motion to the lever, a plurality of display figures, resilient means for mounting the display figures on the lever independently of each other, whereby oscillatory motion is imparted to each of the display figures independently of each other upon oscillation of the lever, the period of oscillation of each of the display figures being independent of each other and of the oscillatory motion of the lever, and whereby the oscillatory motion of the display figures controls the timing of the oscillatory motion of the lever.

4. In an improved animated display device the combination of a base, a lever pivotally mounted intermediate its ends on the base, a solenoid mounted in one end of the base, an electric energizing circuit for said solenoid including a heat controlled thermostatic switch, and whereby the solenoid is intermittently energized, a plunger armature mounted at one end of the lever and cooperating with the solenoid to cause an oscillatory motion on the part of the lever upon energization of the solenoid, a plurality of display figures, each mounted independently of each other and on the lever, the said mountings for the animated display figures being resilient in character and each having an independent period of vibration, and whereby the period of oscillation of the lever by the solenoid is affected by the position of one or more of the animated display figures at the time of energization of the solenoid and a movable weight on the lever for controlling the oscillatory motion thereof independently of the animated display figures and of the solenoid.

ERNST BORREGARD.
